FLUID HEATER CONTROL APPARATUS

Russell F. Dotson, Atlanta, Ga.

Application December 6, 1949, Serial No. 131,473

14 Claims. (Cl. 236—21)

1

This invention relates to fluid heater control apparatus and is particularly well adapted for gas fired installations.

In their efforts to achieve an acceptable degree of safety in this art, prior inventors have almost invariably introduced such complications as to render their devices costly and difficult to maintain. It has now been found that simplicity in this field is highly consistent with maximum safety, and definitely preferable from the standpoints of cost and dependability.

Since apparatus of the type here involved usually comprises a main burner and a pilot burner, it is important that no fuel be supplied to the main burner while an attendant is lighting the pilot burner. Inasmuch as operation of the main burner valve in devices of the type here under consideration is controlled by bleeding fuel from one side of a diaphragm more rapidly than it is replaced from the fuel source, it follows that control of the bleed fuel will determine the opening and closing of the main burner valve. Accordingly, an interlocking arrangement has been provided herein to prevent kindling of the pilot burner at any time that gas can be bled from behind the diaphragm; and furthermore to prevent reopening of the bleed passage until after the pilot burner fuel primer has been released.

Whenever the fluid being heated has reached a temperature exceeding a predetermined safe value, means has been provided for interrupting the flow of both bleed and pilot fuel, requiring manual priming to reestablish the flow of fuel to either the main or pilot burner. A thermocouple exposed to the pilot burner flame supplies current to an electromagnet at a value sufficient to maintain a valve in its open position but insufficient to initiate opening of the valve; hence a manual primer is provided to initiate the opening of such valve, whereupon the pilot burner can be started and the resulting thermocouple current will then hold the valve in its open position.

When the temperature of the fluid being heated drops below a preset value, a thermosensitive element responds to permit the flow of bleed gas, and similarly, when the fluid temperature achieves a predetermined elevated value, the element closes a valve in the bleed gas line. A preferred form of actuator for this purpose assumes the form of a permanent magnet influencing a paramagnetic valve, the magnet being pivotally suspended from a thermally actuated lever having an adjustable fulcrum; and

2

when the safe upper temperature limit has been exceeded, the permanent magnet assumes a position in which its flux opposes that of the thermocouple supplied electromagnet sufficiently for the valve to interrupt the flow of both pilot and bleed gas.

Among its many aspects, the present invention contemplates fluid heater control apparatus comprising a valve casing, a diaphragm dividing the casing into two chambers interconnected by an orifice; means defining a burner supply port, a pilot supply passage and a fuel inlet port communicating with one of the chambers, a valve connected with the diaphragm for registry with the burner supply port, means defining a bleed passage communicating with the other chamber, and a valve interposed in the bleed chamber. The pilot and bleed passages contain valves and suitable operators therefor, the preferred form contemplating an adjusting valve for pilot fuel, a stop valve for bleed fuel, a manual shut-off valve for bleed fuel, and a stop valve for both pilot and bleed fuel. The stop valve for bleed fuel is rendered responsive to the temperature of the fluid being heated, and the stop valve for both pilot and bleed fuel is controlled by the joint effects of pilot burner temperature and temperature of the fluid to be heated. The combined pilot and bleed fuel shut-off valve located in a passage common to the pilot and bleed fuel is equipped with a manual operator for priming during a pilot kindling operation, which operator is rendered ineffective whenever the bleed fuel manual shut-off valve is open; and similarly, when the operator is in a priming position, the manual shut-off valve cannot be opened.

The burner supply valve is biased towards its port closing position by means of a spring, inasmuch as the diaphragm by which it is carried is arranged in a substantially vertical plane, sacrificing the biasing effect of gravity ordinarily utilized in such structures for the added advantages of main burner low gas pressure cut-off and compactness. The burner valve preferably reciprocates between its extreme positions in a recess converging towards its port, the reduced portion of the recess having a cross section substantially equal to that of the valve body.

The bleed passage contains a valve, preferably a paramagnetic ball, influenced by a paramagnetic operator magnetically coupled thereto, which is in turn adjusted by a thermal sensing means which may respond to the temperature of a

fluid to be heated. The combined pilot and bleed fuel shut-off valve is maintained open against the biasing effect of gravity by an electromagnetic means energized by thermal sensing means, the electromagnetic means being opposed in its effect by the magnetic means for controlling the paramagnetic bleed valve. The electromagnetic means preferably responds to pilot temperatures through the use of a thermocouple, and the opposing magnetic means preferably responds to fluid temperatures. The opposing magnetic means is preferably a permanent magnet movable about an adjustable axis to shift the bleed valve and a fluid temperature responsive element is preferably connected with the magnet to effect movement thereof.

Thus it will be recognized that a fluid temperature responsive valve, a manually operated valve, and a pilot temperature responsive valve are interposed in series in the passage travelled by bleed fuel.

Partially due to the lag in the opening and closing of the snap acting main burner supply valve, produced by differential pressure and throttling effects upon its flexible port engaging member, bleed fuel is supplied to the pilot burner just prior to the supply of fuel to the main burner.

The diaphragm and main burner valve biasing spring provides a low gas pressure cut-off for the main burner while permitting the pilot burner to continue operation. Furthermore, this biasing spring permits operation of the main burner only during periods when the gas supply pressure is sufficiently high to insure its efficient operation.

The objects of this invention include the achievement of the foregoing functions, in a practicable and simple manner by novel relationships of parts which can best be described with reference to the accompanying drawings wherein:

Fig. 1 is a side elevation, partially in section, depicting a form of the invention applied to a domestic gas water heater;

Fig. 2 is a front elevation, on a somewhat larger scale, of the control apparatus of Fig. 1;

Fig. 3 is a sectional elevation, on a further enlarged scale, taken along line 3-3 of Fig. 2;

Fig. 4 is a fragmentary sectional elevation, on an enlarged scale, along line 4-4 of Fig. 2;

Fig. 5 is a fragmentary sectional plan view taken along line 5-5 of Fig. 3;

Fig. 6 is a fragmentary sectional elevation taken along line 6-6 of Fig. 5; and

Fig. 7 is a fragmentary sectional elevation taken along line 7-7 of Fig. 2.

The invention has been depicted as applied to a gas water heater comprising a storage tank 10 having a head 12 and bottom 14, from which a depending skirt 16 extends to a pan 18 to define a firebox 20. A main burner 22 provided with the usual bottle mixer 24 is received on brackets 26 which are suitably secured to the pan 18. A mounting plate 28 secured to the forward portion of the firebox, supports the control apparatus of the present invention, generally depicted by reference character 30, whose orifice spud projects through an opening in the mounting plate into the bottle mixer, suitable clamping nuts 32 carried by the threaded spud, engaging opposite surfaces of the mounting plate. The control apparatus comprises a valve casing 34 having a cover plate 36, above which a lever housing 38 is supported, the upper end of which

communicates with a fulcrum housing 40, which in turn receives a thermostatic element 42 intended to respond to temperatures of the fluid to be heated, in this case, water. An adjusting knob 44 is arranged at the front of the fulcrum housing 40, the functions of which will be described in the material to follow. Gas from a suitable source is conducted to the control apparatus through a suitable pipe line 46 which

10 communicates with an inlet nipple 48.

A pilot burner 50 is also located in the firebox 20, serving to ignite fuel supplied to the main burner 22. The pilot burner receives pilot fuel, as well as bleed fuel as will be described, through 15 a tube 52 which communicates with the upper portion of the valve casing 34 as shown in Fig. 1. A thermocouple 54 is mounted above the pilot burner 50 so as to generate a current as result of pilot burner operation, the thermocouple being connected by its cable 56 with the terminals 20 of an electromagnet 58 suitably supported on the valve casing 34.

As depicted in Fig. 1, the storage tank is provided with the usual drop tube 60 and hot water outlet 62.

25 A diaphragm 64 is clamped between the valve casing 34 and cover plate 36 by means of screws 66, the diaphragm being penetrated by a small orifice 68 through which gas supplied by the 30 nipple 48 to the internally threaded inlet port 70, can pass from a chamber 72 formed at one side of the diaphragm to a chamber 74 formed at the other side thereof. In order to maintain the apparatus as compact as is consistent with 35 highly satisfactory operation, the diaphragm 64 is composed of a relatively flexible material so that it can partake of sufficient movement to permit proper opening and closing of the main burner supply valve 76. The valve 76 comprises 40 a rigid backing plate or disc 78 secured to an internally threaded collar 80 threaded to its proper position upon a stem 82, and a flexible seat engaging member 84 centrally clamped against the backing plate by means of a nut 86 45 likewise threaded on the stem 82. The valve 45 stem 82 is provided with a head 88, between which and the flexible diaphragm 64, a relatively large rigid disc 90 is interposed. The diaphragm 64 is centrally clamped against the disc 90 by means 50 of a nut 92 threaded on the stem 82. A reduced portion of the stem 82 projects beyond the main burner valve to serve as a guide pin 94 which is received in a tubular bearing 96 formed 55 centrally of the externally threaded nipple 98 which receives the orifice spud. A spring 100 is interposed between the valve casing cover 36 and the diaphragm 64 tending to urge the main burner valve 76 towards its seat 102 located at the 60 lower end of a recess 104 formed in the valve casing, having a side wall 106 converging towards the burner supply port. The valve casing cover 34 is centrally threaded to receive a 65 limiting stop 108 whose position can be adjusted by means of a screwdriver after removing the dust cover 110 in order to limit the maximum departure of the main burner supply valve 76 from its seat to conform with the requirements of burners of different capacities. It will be advantageous to describe the operation of the main burner supply valve at this point. Assuming that the valve 76 has moved to its extreme right hand position as viewed in Fig. 3 to close its port, and assuming that the chambers 72 and 74 are filled with gas, and further assuming that there is a 70 call for gas to the main burner, which will 75

result in a bleeding of gas from the chamber 74 more rapidly than it can be replenished through the relatively small orifice 68 formed in the diaphragm, the forces tending to open the valve will consist of gas at the pressure supplied to chamber 72 acting on an area of the flexible seat engaging member 84 extending beyond the seat itself and gas at this same pressure acting on the portion of the diaphragm supported by the rigid disc 90; the opposing forces tending to maintain the valve closed consist of the pressure of the gas in chamber 72 acting on the exposed area of the backing plate 76 and gas at the pressure extant in chamber 74 acting on the rigid disc 90 and in addition, the force of the spring 100. As soon as the summation of opening forces exceeds the opposing forces, the diaphragm and the valve stem 82 begin to move to the left as viewed in Fig. 3, but since gas at the pressure existing in chamber 72 will gain access to the space between the rigid backing plate 72 and flexible seat engaging member 84 of the valve, it will follow that the flexible seat engaging member 84 will tend to remain on its seat as long as its flexibility will permit. However, as soon as the diaphragm 64 has moved sufficiently far to the left, the flexible seat engaging member 84 will be snapped from its seat to produce a full flow of gas to the burner almost immediately. When gas is no longer being bled from the chamber 74, its pressure will become equal to that prevailing in chamber 72, whereupon the diaphragm will tend to seek its neutral position insofar as the gas pressures alone are concerned, but the spring 100 biases the diaphragm and its valve towards the right as viewed in Fig. 3 so that the valve moves towards its seat with an ever diminishing distance from the convergent wall 106 to produce a throttling effect as the valve approaches its seat, which results in a cushioning effect which has been found to be so desirable during the closing operation.

Gas is bled from the chamber 74 through a passage 112 which communicates with a valve chamber 114 formed in the upper portion of the cover plate 36. The valve chamber 114 has a cylindrical wall 116 which is slightly downwardly inclined towards the right as viewed in Fig. 3, the lowermost portion communicating with a passage 118 defining a seat for the paramagnetic valve ball 120 housed in the chamber 114. The upper end of the valve chamber 114 is closed with respect to atmosphere by means of a plug 122. The passage 118 registers with a perforation 124 formed through the diaphragm, which in turn registers with a passage 126 formed in the valve casing 34. As clearly shown in Fig. 5 of the drawings, the passage 126 can be closed by means of a rotary valve 128 whose plug 130 has secured thereto a latching member 132 which serves as a handle to shift the valve through an angle of 90° from open to closed position. The passage 126 intersects a passage 134 at right angles thereto, one end of which terminates at its intersection with a ball chamber 136, and the other end of which is internally threaded to receive a pilot flow adjusting screw or valve 138 and a dust cover 140. The valve 138 is provided with a graduated orifice forming portion 142 which provides a substantially circular, and therefore self-cleaning orifice in all of its positions to which it can be adjusted. This valve controls the flow of gas from the chamber

72 through a passage 144 which intersects the passage 134 at right angles.

It will be evident that the pilot gas passage 144 and the bleed gas passage 126 communicate with one another through the common passage 134, so that they will be jointly controlled by a valve ball 146 received in the ball chamber 136. The electromagnet 58, shown particularly in Figs. 6 and 7, as previously described, is energized by current from the thermocouple 54 in response to temperature conditions at the pilot burner. The core 148 of the electromagnet is threaded near its lower end to secure it at the upper end of the ball chamber 136. The lowermost end of the core 148 is sharply tapered to obtain a concentration of flux, but the force of the magnet is never sufficient in itself to elevate the ball 146 from the position shown in Fig. 6 in which it closes its passage 150, but the force of the electromagnet is sufficient when the pilot burner is operating to retain the ball 146 in an elevated position once it has been raised into contact therewith. Accordingly, manually actuated means in the form of an operator or primer has been provided, comprising a rod 152 of non-magnetic material, having a tapered end 154 for engagement of the ball slightly below its center, so that when the rod is advanced towards the right as viewed in Fig. 6, the ball will be elevated into contact with the tapered end of the core 148. The rod 152 is received within a bore 156 which communicates with the lower portion of the ball chamber 136. The rod is preferably biased outwardly by means of a spring 158 which bears upon a shoulder 160 formed in the bore and upon a collar 162 carried by the rod. The rod is centered in the bore 156 by means of a bushing 164 threaded into the end of the bore. The outer end of the rod 152 carries a push button 166 by which the rod can be depressed in opposition to the spring 158 to elevate the ball 146, but only during such times as the bleed valve 128 closes its passage 126. This is accomplished by arranging the valve handle or latching member 132 so that it will always assume a position in the path of the push button 166 whenever the bleed valve 128 assumes an open position. Moreover, once the latching member 132 has been swung counterclockwise sufficiently to permit depression of the push button 166, the latching member 132 cannot be moved clockwise to open its valve 128 so long as the push button 166 remains depressed. Thus, there is no possibility of the main burner being supplied with gas during a priming operation. It is also impossible to adjust the pilot flow valve 138 while the bleed gas valve 128 is open, since the latching member or operator 132 likewise obstructs access to the valve 138 and its dust cover 140 when the bleed gas valve 128 is open, but counterclockwise movement of the latching member or operator 132 sufficiently to afford access to the valve 138 will assure closure of the valve 128. The latching member or operator 132 is provided with a suitable limiting stop 168 to prevent such excessive movement of the valve 128 as would defeat the purpose of this arrangement. With the valve ball 146 in its elevated position, both pilot and bleed gas can flow downwardly through the passage 150 to its intersection with a passage 170 terminating in a threaded nipple 172 to which the pilot tube 52 is secured in fluid tight relation.

The lever housing 38 surmounting the valve casing, receives in its upper end a depending tubular portion 174 of the fulcrum housing 40.

The housing 40 is provided with an internally threaded opening 176 which receives an internally and externally threaded bushing 178 whose inner end is bifurcated to define a guide slot 180 to limit lateral movement of a fulcrum plate 182. The plate 182 contains an opening 184 which loosely receives the reduced end 186 of a threaded shaft 188 received by the internal threads of the bushing 178. The adjusting knob 44 is secured to the exposed end of the shaft 188 to shift the axis about which the plate 182 will move during its operation. The lower portion of the plate 182 is biased towards the right as viewed in Fig. 3, by means of a spring 190 which is centered and retained by means of a screw 192 which also serves to maintain the lever housing and fulcrum housing in assembled relationship. The lower end of the plate 182 is drilled to receive the upper end of a resilient lever 194, the upper portion of which contains a loop 196 which will yield under severe conditions to prevent damage to the operating parts, and at the same time permitting them to retain their preset relationships. The lower end of the lever 194 receives a link 198 pivotally connecting it with a permanent magnet 200 whose lower end traverses a path lying below, though spaced from, the center of the ball 120. As will be evident from an inspection of Fig. 3, the permanent magnet receives the link 198 near one corner thereof, so that in its terminal right hand position as shown in Fig. 3, the magnet assumes a position which is somewhat inclined to the vertical in the interests of compactness. This permanent magnet 200 also controls the valve ball 120 located in the valve chamber 114, serving to control the flow of bleed gas from the chamber 14 in response to temperature conditions of the fluid to be heated. When the system requires operation of the main burner as determined by the temperature of the fluid to be heated, the lever 194 moves towards the left as viewed in Fig. 3, carrying the permanent magnet 200 with it until such time as the lowermost end of the permanent magnet approaches the ball 120 sufficiently closely to cause relative movement of the magnet and ball. At this point, the magnet will swing about the pivot defined by the link 198 to the most proximate position with respect to the ball permitted by the position of the lever 194. Under these conditions, the ball 120 will be lifted towards the upper portion of its inclined chamber to open the passage 118 to the flow of bleed gas passing from the chamber 14 through the passage 112. As the fluid to be heated achieves the temperature corresponding to the predetermined setting effected by adjustment of the knob 44, the lever 194 begins moving towards the right as viewed in Fig. 3, effecting a corresponding direction of movement of the permanent magnet 200, the permanent magnet remaining at all times in as close proximity to the ball 120 as the position of the lever 194 will permit, until finally the force imposed by the lever 194 upon the permanent magnet 200 exceeds the attractive force between the permanent magnet and the ball 120, at which time the magnet will be pulled away from the ball and the passage 118 will be closed to block the further flow of the gas from the chamber 14.

The fulcrum housing 40 supports a lever 202 upon a pivot 204, the lower end of the lever terminating in a point 206 which bears upon a portion of the fulcrum plate 182 intermediate the shaft 188 and the spring 190. The upper end of the lever 202 is engaged by a rod 208 which transmits movements of its housing 210

in response to expansion and contraction of the housing resulting from temperature conditions to which it is subjected. In this case, the housing member 210 may assume the form of a copper tube having a closed end, the tube being depicted in Fig. 1 as in contact with the wall of a storage tank of a water heater. It will be clear than an increase in temperature of the fluid to be heated will result in an expansion of the tube, reducing the force of the rod 208 upon the lever 202, resulting in movement of the lever 194 towards the right under the influence of its biasing spring 190. Conversely, when the liquid to be heated has cooled to a predetermined point, the effects will be reversed, the lever 194 will move towards the left and the valve 120 will be lifted from its seat.

Should the temperature of the fluid to be heated rise above that for which the knob 44 has been adjusted, the lever 194 will continue to move towards the right, carrying the permanent magnet 200 with it, until such time as the flux of the permanent magnet 200 will oppose that of the electromagnet sufficiently to cause the valve ball 146 to drop to its seat to close the passage 150, thereby obstructing the flow of both pilot gas and bleed gas, calling for a manual reset before service can be resumed. As previously described, such a reset would require closing the bleed gas valve 128 in order to depress the push button 166 to elevate the ball 146 and permit the passage of pilot gas so that the pilot can be ignited. Then, before the main burner can go into operation, the push button 166 must be released and the operator 132 restored to its obstructing position to open the bleed gas valve 128. It should be noted in this behalf that as long as the permanent magnet assumes a position in which its flux opposes that of the electromagnet sufficiently to prevent retention of the ball in an elevated position, operation of the system cannot be resumed since the ball 146 will always return to its seat as soon as the push button 166 has been released.

One condition under which such complete shut-down of the main and pilot burners is produced, occurs when there is stoppage due to dirt or other causes of the diaphragm orifice 68. Under these conditions, no gas can pass directly from the chamber 72 into the chamber 14 through the orifice, and accordingly, excessive heating will eventually cause the ball 146 to drop to its seat and block the passage of both pilot and bleed gas. As soon as the ball 146 drops to its seat, continued flow of pilot gas through passages 144 and 134 will produce a flow through passage 126, back through the passage 118 and past the valve 120, through the passage 112 into chamber 14 until gas pressure in the chamber 14 builds up sufficiently to move the main burner valve 16 to its seat 102, preventing the further flow of fuel to the main burner until such time as the system may be manually reset.

This control apparatus readily adapts itself to permit a shutting down of the main burner for a protracted period while maintaining operation of the pilot burner. This is accomplished simply by moving the latching member or operator 132 counterclockwise to a position closing the bleed gas valve 128 and maintaining the operator 132 in this position for such period of time as may be desired. To restore the system to operation under these conditions, it is merely necessary to rotate the operator 132 clockwise until the bleed gas valve 128 is reopened.

The knob 44 can be adjusted to move the axis or fulcrum about which the lever 194 is pivoted to adjust the temperature to which the fluid to be heated will be raised. In the event that it is desired to produce a complete shut-down of the system by adjustments of the knob 44, it is merely necessary to turn it to a position in which the permanent magnet 209 will oppose the electromagnet 58 sufficiently to cause the ball 146 to drop to its seat just as in the case of excessive heating of the fluid. Here again, when it is desired to restore the system to operation, manual resetting will be required. This will be possible of course, only after the knob has been shifted from the aforesaid position to a setting of temperature within the operating limits of the system.

It will be understood that in order for the electromagnet and permanent magnet to influence the valve balls, the adjacent portions of the valve casing, its cover, and other adjacent structures will be composed of non-magnetic materials.

This application is a continuation-in-part of application Serial Number 778,970, filed October 9, 1947, now abandoned, and entitled "Automatic Liquid Temperature Control Device."

Whereas only one form of the invention has been described with reference to the accompanying drawings, many variations will suggest themselves to those skilled in the art after reading this specification, just as such variations have already occurred to the present inventor. Accordingly, the invention should not be restricted to the specific structure depicted and described beyond the scope of the appended claims.

I claim:

1. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said bleed passage, a valve interposed in said pilot supply passage, a manual operator for said pilot supply valve and means interconnected with said bleed passage valve obstructing said operator when said bleed passage valve is open.

2. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said bleed passage, a valve interposed in said pilot supply passage, a manual operator for said pilot valve, a manual operator for said bleed valve providing means interconnected therewith obstructing said pilot valve operator while said bleed valve is open.

3. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a

valve interposed in said bleed passage, a valve interposed in said pilot supply passage, manual operators for said bleed and pilot valves, and means interconnected with said pilot valve operator obstructing said bleed valve operator when said pilot valve operator occupies a valve opening position.

4. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said pilot supply passage, said passages communicating beyond said valves with a common passage, and a valve interposed in said common passage.

5. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said bleed passage, means defining a passage common to said bleed and pilot passages, a valve interposed in said common passage, an operator for said common passage valve, and means obstructing said operator when said bleed passage valve is open.

6. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a paramagnetic valve interposed in said bleed passage, a paramagnetic operator magnetically coupled with said bleed passage valve, and thermal sensing means connected with said operator.

7. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said bleed passage, means defining a passage common to said bleed and pilot passages, a valve interposed in said common passage, electromagnetic means for holding said common passage valve open, thermal sensing means connected with said electromagnetic means for energizing the same, and thermally actuated magnetic means controlling said bleed valve and of opposite polarity to the field of said electromagnetic means.

8. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner

supply port, means defining a bleed passage communicating with the other of said chambers, a valve interposed in said bleed passage, a valve interposed in said pilot passage, electromagnetic means responsive to pilot temperature for holding said pilot valve open, and magnetic means responsive to fluid temperature to oppose the field of said electromagnetic means.

9. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said bleed passage, a valve interposed in said pilot passage, an operator for said bleed valve, said operator obstructing access to said pilot valve when said bleed valve is open.

10. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a valve interposed in said bleed passage, said passages combining to form a common passage, a valve in said common passage biased towards a closed position, an electromagnet supporting said biased valve in open position, a pilot responsive thermocouple energizing said electromagnet, and a manual operator for shifting said biased valve towards said electromagnet.

11. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a paramagnetic valve interposed in said bleed passage, a permanent magnet movable about an axis to shift said bleed valve, a fluid temperature responsive element connected with said magnet to effect movement thereof, and adjusting means for shifting said axis.

12. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner

supply port, means defining a bleed passage communicating with the other of said chambers, a paramagnetic valve body interposed in said bleed passage, a movable magnet spaced from said bleed valve having a field directly operable on said bleed valve for shifting the same between passage opening and closing positions, and fluid temperature responsive means connected with said magnet for imparting valve shifting movement thereto.

13. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a paramagnetic valve body interposed in said bleed passage, a pilot tube in fluid communication with said pilot and bleed passages, and means including a permanent magnet actuating said bleed valve responsive to fluid temperature to supply bleed fuel to said pilot prior to opening of said burner supply valve.

14. Fluid heater control apparatus comprising a valve casing, a diaphragm dividing said casing into two chambers interconnected by an orifice; means defining a burner supply port, a pilot supply passage and a fuel inlet port communicating with one of said chambers; a valve connected with said diaphragm for registry with said burner supply port, means defining a bleed passage communicating with the other of said chambers, a gravity biased ball valve interposed in said bleed passage and tending to close the same, pilot temperature responsive means exerting a force sufficient to maintain said ball in open position but insufficient to elevate said ball to open position, and an operator engageable with said ball to elevate it to open position.

RUSSELL F. DOTSON.
